RACKET STRING TIGHTENING MACHINE

Joseph Saladino, Reading, Mass.

Application February 14, 1935, Serial No. 6,501

14 Claims. (Cl. 273—73)

This invention relates to improvements in a racket string tightening machine.

One object of my invention is to improve the means whereby the racket string tightening machine is automatically stopped in the string tightening operation when a predetermined point is reached. It is highly desirable to pull each string to a certain degree of tightness, and in this operation, when actuating the lever or other actuating means it is much easier for the operator to safely to be able to actuate it to the limit, instead of having to watch the gauge, and ceasing the actuating movement when the gauge reaches a certain point. Accordingly, I have improved the construction of the means for automatically limiting the actuating movement. Also it has been positioned with respect to the other parts of the machine where it may readily be adjusted when a change in the limit of the actuating movement is desired.

Another object of my invention is to improve upon the rotatable tightening device so that the string may be tightened with a minimum actuating movement, thereby making the work of the operator easy, and giving my machine a greater range of adjustability.

The foregoing and other objects which will appear as the nature of the invention is better understood, may be accomplished by a construction, combination and operative arrangement of parts such as is disclosed by the drawing. The nature of the invention is such as to render it susceptible to various changes and modifications, and, therefore, I am not to be limited to the construction disclosed by the drawing; but am entitled to all such changes therefrom as fall within the scope of my claims.

In the drawing:

Figure 1 is a side elevation view of my machine for tightening racket strings.

Figure 2 is a plan view showing the tensioning device.

Figure 3 is a section taken on the line 3—3 of Figure 2.

As illustrated, my racket string tightening machine has a base 15 supporting a vertical standard 16. My machine is actuated by depressing a treadle 18 which is pivoted as at 19 to a bracket 20 which is held to said base 15. A convenient shelf 22 is mounted on said standard 16 to hold tools or other articles. A bracket 23 is mounted on said standard 16 and extends to the front of the machine, supporting the tension device, and also cooperating with the automatic stop means to limit the downward movement of said treadle

18 to a predetermined point, a portion of said stop means extending through a hole 25 in an extension portion 24 of said bracket 23. Said automatic stop means has an adjusting rod 26 which is slidably mounted in said hole 25 and has a screw threaded portion 27 which screws part way into a socket 28, which is pivotally mounted on a pin 29 between upstanding ears 30, said pin being held in position by a cotter pin 31. Adjustment of my said automatic stop means may be made by screwing said adjusting rod 26; but it is ordinarily made by a collar 35 on said rod, later described. At the top of my said adjusting rod 26 is a wing nut 33 fixed thereto by a pin 34. Below said nut is a stop member in the form of an adjusting collar 35 slidably mounted on said rod 26 which is held in a predetermined position by a set screw 36. When said collar, which is fixedly held in place by said set screw 36, contacts said bracket extension 24, the downward movement of said treadle 18 is stopped, and the position of said collar 35 determines the extent of said downward movement. Inasmuch as the depression of said treadle 18 also actuates the tensioning device 50 later described, when said collar 35 contacts said extension 24 the movement of the tensioning device 50 also stops.

My machine has a rotatable racket support or holder 40 consisting of a frame 41 and a top 42, on which are mounted racket holding clamps 43 which are operated by thumb screws 44. The upstanding portions 45 of said clamps 43 are recessed as at 46 to receive an insert 47 of leather or other material that will not scratch or mar the racket when the said clamps 43 are tightened.

The strings extending from the tennis racket 48 are drawn tight by a tensioning device 50 supported by said bracket 23, which device has a pulley 51 connected to which is a cable 52 which is fastened at one end as at 53 to said treadle 18 and has a spring 54 connected to the other end which spring is connected to a plate 55 which is screwed as at 56 to said base 15. It will readily be seen that the depression of said treadle 18 will rotate said tension device 50 to which a racket string may be fastened, in which event said string will be tightened. Said tension device has a housing 59, a barrel portion 60 which has a bulge or raised portion 61. A cleat 62 on said barrel 60 is adapted to receive the string from the racket, and when said string is fastened thereto rotation of said tensioning device 50 tightens said string. A scale 63 near one end of said tensioning device together with the pointer

64 indicates the degree of tightness to which the string has been pulled. Inside said barrel is a spring 66 which is compressed when said tensioning device is rotated. A description of the 5 construction and operation of said tensioning device was made in my patent application, Serial No. 737,562, filing date July 30, 1934. As said tensioning device 50 is rotated to tighten the string said raised portion 61, by the lift it gives to the 10 string, helps to tighten it, cooperating with the means for actuating said tensioning device 50 so that said treadle 18 need not be depressed so far because of it.

What I claim is:

- 15 1. A racket string tightening machine comprising in combination, supporting means for a racket, instrumentalities adapted to receive and upon actuation to tighten a string in a racket embodying a tensioning device, movable means 20 to actuate said instrumentalities, and mechanism in front of said tensioning device connected to said movable means adapted to limit said actuating movement.
- 25 2. A racket string tightening machine comprising in combination, supporting means for a racket, instrumentalities adapted to receive and upon actuation to tighten a string in a racket embodying a tensioning device, movable means 20 to actuate said instrumentalities, and mechanism 30 in front of said tensioning device and operatively connected to said movable means adapted to limit said actuating movement, said mechanism embodying a stop member.
- 35 3. A racket string tightening machine comprising in combination, supporting means for a racket, instrumentalities adapted to receive and upon actuation to tighten a string in a racket, movable means to actuate said instrumentalities, a bracket extending from said supporting means, 40 and mechanism operatively connected to said movable means adapted to limit said actuating movement, a portion of said mechanism being slidably mounted in said bracket.
- 45 4. A racket string tightening machine comprising in combination, supporting means for a racket, instrumentalities adapted to receive and upon actuation to tighten a string in a racket, movable means to actuate said instrumentalities, a bracket extending from said supporting means having a hole therein, and mechanism operatively 50 connected to said movable means adapted to limit said actuating movement, said mechanism embodying a rod slidably mounted in said hole.
- 55 5. A racket string tightening machine comprising in combination, supporting means for a racket, instrumentalities adapted to receive and upon actuation to tighten a string in a racket, movable means to actuate said instrumentalities, a bracket extending from said supporting means having a hole therein, and mechanism operatively 60 connected to said movable means adapted to limit said actuating movement, said mechanism embodying a rod slidably mounted in said hole, a stop member mounted on said rod above said hole, said member being adapted to contact with said bracket during actuation of said movable means whereby said actuating movement is stopped.
- 65 70 6. A racket string tightening machine comprising in combination, supporting means for a racket, instrumentalities adapted to receive and upon actuation to tighten a string in a racket, movable means to actuate said instrumentalities, 75 a bracket extending from said supporting means

having a hole therein, and mechanism operatively connected to said movable means adapted to limit said actuating movement, said mechanism embodying a rod slidably mounted in said hole, a collar mounted on said rod, means to hold said collar in a predetermined position on said rod whereby actuation of said movable means brings said collar into contact with said bracket to thereby stop said actuation at a predetermined point.

7. A racket string tightening machine comprising in combination supporting means for a racket, instrumentalities adapted to receive and upon actuation to tighten a string in a racket embodying a tensioning device, movable means 15 to actuate said instrumentalities, mechanism operatively connected to said movable means adapted to limit said actuating movement, a bracket extending from said supporting means on which said tensioning device is mounted, said bracket 20 embodying an extension, extending forward of said tensioning device, said extension having a hole therein, said mechanism embodying a rod extending through said hole, a stop member on said rod above said hole adapted to contact with 25 said extension when said movable means have been actuated to a predetermined point.

8. A racket string tightening machine comprising in combination, supporting means for a racket, instrumentalities adapted to receive and 30 upon actuation to tighten a string in a racket embodying a tensioning device, movable means to actuate said instrumentalities, mechanism operatively connected to said movable means adapted to limit said actuating movement, a bracket 35 extending from said supporting means on which said tensioning device is mounted, said bracket embodying an extension extending forward of said tensioning device, said extension having a hole therein, said mechanism embodying a rod 40 slidably extending through said hole, a stop member movably mounted on said rod above said hole, means to hold said stop member in a fixed predetermined position on said rod whereby said stop member will contact with said extension during 45 actuation of said movable means to thereby stop said actuation.

9. A racket string tightening machine comprising in combination, supporting means for a racket, instrumentalities adapted to receive and 50 upon actuation to tighten a string in a racket embodying a tensioning device, a bracket extending from said supporting means, movable means to actuate said instrumentalities, mechanism operatively connected to said movable 55 means adapted to limit said actuating movement, said mechanism embodying a rod connected with said movable means, a stop member movably mounted on said rod at the upper portion thereof, means to hold said stop member in a 60 fixed predetermined position on said rod, said stop member being adapted during actuation of said movable means to contact with said bracket to thereby stop said actuation at a predetermined point.

10. A racket string tightening machine comprising in combination, supporting means for a racket, instrumentalities adapted to receive and upon actuation to tighten a string in a racket embodying a tensioning device, a bracket 70 extending from said supporting means, movable means to actuate said instrumentalities, embodying a treadle, mechanism operatively connected to said movable means adapted to limit said actuating movement, said mechanism embodying 75

a rod, means connecting said rod to said treadle, a portion of said rod being adjacent said bracket, a stop member on said rod so positioned that it is adapted to contact with said bracket during actuation of said movable means to thereby stop said actuation at a predetermined point.

11. A racket string tightening machine comprising in combination, supporting means for a racket, instrumentalities adapted to receive and upon actuation to tighten a string in a racket embodying a tensioning device, a bracket extending from said supporting means embodying a front extension, movable means to actuate said instrumentalities embodying a treadle, mechanism operatively connected to said movable means adapted to limit said actuating movement, said mechanism embodying a rod slidably mounted in said front extension, a socket connected to said treadle, said rod being adjustably connected to said socket, a stop member movably mounted on said rod at the upper portion thereof above said bracket, means to hold said stop member on said rod in a fixed, predetermined position, said stop member being adapted during actuation of said movable means to contact with said extension to thereby stop said actuation at a predetermined point.

12. A racket string tightening machine comprising in combination, supporting means for a racket, instrumentalities adapted to receive and upon actuation to tighten a string in a racket embodying a tensioning device, a bracket extending from said supporting means embodying a front extension, movable means to actuate said instrumentalities embodying a treadle, mechanism operatively connected to said movable means adapted to limit said actuating movement, said

mechanism embodying a rod slidably mounted in said front extension and being threaded at its lower portion, a socket movably connected to said treadle having a screw threaded portion adapted to receive the said threaded portion of said rod, 5 a stop collar slidably mounted on said rod above said extension, means to hold said stop collar on said rod in a fixed predetermined position, said stop member being so positioned that during actuation of said movable means it will contact 10 with said extension to thereby stop said actuation at a predetermined point.

13. A racket string tightening machine comprising in combination, supporting means for a racket, instrumentalities adapted to receive and upon actuation to tighten a string in a racket, movable means to actuate said instrumentalities, embodying a treadle, mechanism operatively connected to said treadle adapted to limit said actuating movement, said mechanism 15 embodying a rod and a stop member mounted on said rod, and pivot means pivotally connecting said rod to said treadle.

14. A racket string tightening machine comprising in combination, supporting means for a racket, instrumentalities adapted upon actuation to tighten a string in a racket embodying a rotatable device adapted to receive and hold said string, movable means to actuate said instrumentalities, said rotatable device embodying 25 a barrel having a raised portion over which the string to be tightened passes prior to the point where it is held and received by said device, whereby said raised portion cooperates with said movable means to tighten said string. 35

JOSEPH SALADINO.
